FIG. 1.

FIG. 2.

FIG. 3.

FIG. 4.

FIG. 5.

FIG. 6.

FIG. 1 is a front elevational view of a garment hanger showing my new design;

FIG. 2 is a top plan thereof;

FIG. 3 is a side-elevational view thereof;

FIG. 4 is a front elevation view of a modified form of the garment hanger shown in FIG. 1;

FIG. 5 is a top plan view of FIG. 4, and

FIG. 6 is a side-elevational view of FIG. 4.

The characteristic features of this design reside in the recessed nature of the pants-supporting bar as indicated in FIGS. 2 and 5.

This application is a continuation-in-part of design application Ser. No. D. 10,140, filed Jan. 12, 1968, now abandoned.

I claim:

The ornamental design for a garment hanger, substantially as shown and described.
